VEHICLE STEERING WHEEL TRAY

Rufus P. Steadman, Saginaw, Mich.

Application April 26, 1948, Serial No. 145,957

Term of patent 14 years

(Cl. D14—6)

To all whom it may concern:

Be it known that I, Rufus P. Steadman, a citizen of the United States of America, residing at Saginaw, in the county of Saginaw and State of Michigan, have invented a new, original, and ornamental Design for a Vehicle Steering Wheel Tray, of which the following is a specification, reference being had to the accompanying drawing, forming part thereof.

In the drawing:

Fig. 1 is a side elevational view of a vehicle steering wheel tray showing my new design.

Fig. 2 is a top, plan view; and,

Fig. 3 is a top, perspective view showing the top support as it appears when in open position.

The dotted line showing of a steering wheel in Fig. 2 is for illustrative purposes only. The characteristic features of my design reside in the portion shown by means of full lines in the drawing.

I claim:

The ornamental design for a vehicle steering wheel tray, as shown and described.

RUFUS P. STEADMAN.
